(57) **CLAIM**

The ornamental design for a storage and display unit, as shown and described.

DESCRIPTION

FIG. 1 is a perspective view of the storage and display unit according to the invention.

FIG. 2 is a front view of the storage and display unit.

FIG. 3 is a top view of the storage and display unit.

FIG. 4 is a left side view of storage and display unit.

FIG. 5 is a right side view of the storage and display unit.

FIG. 6 is a bottom view of the storage and display unit; and, FIG. 7 is a rear view of the storage and display unit.

The broken lines are for the purpose of illustrating the environment of the article only and form no part of the claimed design.
